(57) **CLAIM**

The ornamental design for a welding glove as shown and described.

DESCRIPTION

FIG. 1 is an isometric view of a pair of welding gloves showing my new design, the pair including a left hand glove and a right hand glove being a mirror image thereof; FIG. 2 is an isometric view of the left hand glove of the pair of welding gloves of FIG. 1; FIG. 3 is a front elevation view of the left hand glove of FIG. 1; FIG. 4 is a right elevation view of the left hand glove of FIG. 1; FIG. 5 is a left elevation view of the left hand glove of FIG. 1; FIG. 6 is a plan view of the left hand glove of FIG. 1; FIG. 7 is a bottom plan view of the left hand glove of FIG. 1; and, FIG. 8 is a back elevation view of the left hand glove of FIG. 1. The broken lines illustrate portions of the article and form no part of the claimed design.

1 Claim, 6 Drawing Sheets
